JOHAN GUSTAF GRÖNDAL AND CARL LORENS CARLSON, OF STOCKHOLM, SWEDEN, AS-SIGNORS TO PATENTAKTIEBOLAGET GRÖNDAL-RÄMEN, OF STOCKHOLM, SWEDEN, A LIMITED COMPANY

OVEN FOR DRY DISTILLATION OF SHALES AND THE LIKE

Application filed March 18, 1927, Serial No. 176,550, and in Sweden October 7, 1926.

At the distillation of bituminous shales, brown coal and the like ovens have already been used, provided with a grate movable through them and supporting the material, 5 which is heated by passing a current of indifferent gases therethrough. In such ovens, however, the shales become sticky and stop up the openings between the grate bars, thereby preventing the passage of the gases 10 through the shales and necessitating a cleaning of the grate. Such a cleaning, however, is not possible during the process of distillation, which for that reason must be interrupted, whereby a continuous working will 15 be prevented.

another and each passed one or more times by the circulating gases. Because these partitions do not closely fit to the grate or the heating channel the said gases pass successively forward along the oven to the adjacent 50 compartment according as new gases are formed. The steam generated at the distillation of the moist shales, usually containing 15%-20% water, is forced to successively pass through the grate and the shales upon 55 same, whereby as also by the circulation of the gases the sticking together of the shales—viz. the stopping up of the grate and the decomposition of oil gases distilled off will be prevented.

This inconvenience may be avoided by the use of the oven forming the object of our invention, which oven also is provided with a movable grate, but in connection with certain means for prevention of the sticking together of the material viz. the stopping up 60 of the grate.

The oven is of the tunnel type with a grate movable along the tunnel. The grate may be 25 either straight or form an endless track, passing around on rollers or the like. In the oven, ventilators are arranged above the grate with the purpose of sucking away the gases formed during the distillation of the shales and forcing said gases down through 30 channels in the oven walls into the lower part of heating elements, arranged in a channel, heated by means of hot gases from one or more fire places outside the oven. The 35 gases passing through the heating elements hereby will become heated to a temperature, required for the distillation of the shales, rise through the grate with the shales and under the action of the ventilators will continue their circulation in the oven together 40 with new-formed gases. The oven chamber above the grate as also that part of it which is situated under the heating channel, by means of vertical cross partitions is divided 45 in compartments, communicating with one

Should the percentage of water of the shale be under 20% but the shales at the same time be rich in bituminous components more steam must be introduced in the oven. This can be made by cooling the escaping gases, 65 essentially consisting of steam and oil gases, to about 100° C., whereby the greatest portion of the oil will be condensed, while the water remains as steam. A greater or less part of the gases thus cooled is carried back 70 to the oven, whereby a necessary addition of steam then will be realized.

If the quantity of steam introduced in the oven becomes too small because of any negligence in the attention to the oven, and the 75 shales consequently stick together on any part of the grate, the result will be that only such shales as stick together will be incompletely distilled, the shales on the rest of the grate being completely distilled. When the 80 part of the grate carrying the incompletely distilled shales leaves the distillation chamber (see Figures 1-3), this part can be easily cleaned without any interruption of work.

In the drawings, in which like parts are 85 designated by the same reference characters,

Figure 1 is a longitudinal vertical section of a distilling oven according to the invention, provided with a straight track of grate formed by a number of small grates arranged 90

one after the other and carried on rollers or wheels;

Figure 2 is a longitudinal horizontal section thereof;

5 Figure 3 is a transverse vertical section thereof;

Figure 4 is a longitudinal vertical section of a modification of the invention;

10 Figure 5 is a longitudinal horizontal section of the modification;

Figure 6 is a transverse vertical section of the modification;

Figure 7 is a transverse vertical section of another modification of the invention; and

15 15 Figure 8 is a detail of the chain grate and driving wheel shown in Figures 4, 5, 6 and 7.

The tunnel oven is provided with a longitudinal channel D; in Fig. 1 it is shown to be divided in several compartments d , d' , d'' , 20 which can be shut by means of dampers x , x' , x'' , x^3 . The compartment d and d'' form chambers in which the material is retained before and after the distillation in the intermediate compartment d' . The oven D, however, can also consist of a single, undivided 25 channel as shown in Figs. 4, 5.

In the constructional form illustrated in Figs. 1-3 the grate is formed by a number of separate, movable grates each consisting 30 of grate bars or perforated plates A, supported by rollers or wheels C and surrounded by an upstanding edge B, the height of which suitably corresponds to the thickness of the layer of shales upon the grate. e are the ventilators for removal of the gases of distillation from the shales, and f the channels in the side walls of the oven, through which channels the said gases are forced to the heating elements g , arranged in the heating channels h , i . In place of two such heating channels only one i may be used as illustrated in 40 Figs. 4, 5. k and k' represent the partition walls for the division of the oven chamber in several compartments.

45 This grate is moved through the furnace in the following manner. The dampers x' and x^2 are open and by means of the device o the grates A, connected with one another, are fed to the chamber d' , from which a corresponding number of grates is removed to the chamber d'' . The dampers x' and x^2 now are shut, x and x^3 opened and new charged grates are introduced in the fore chamber d , whereupon the damper x is shut. Simultaneously the 50 grates in the chamber d'' are removed and the damper x^3 shut, whereupon the operation now described is repeated.

It will be suitable to have the length of the chambers d and d'' as large as possible, because in such a case it will not become necessary so often to open the dampers x and x^3 , which provide the connection with the outer air, and thus to save the heat.

55 In place of the constructional form of the oven, now described, the modified form, illus-

trated in Figs. 4-8 may be used, in which the grate consists of a chain grate, formed by sets of links 2, connected by cross bolts 3 and separated from each other by interspaces of about the same width as that of the links. 70 This endless chain grate is supported by rollers 14 and provided with upstanding edges 11 for preventing the dragging of the shales or the like against the walls of the oven. The grate moves over two drums 4, 5, of which the first one 4, forming the driving drum, is provided with shoulders or projections 6, corresponding to the openings in the chain grate and having about the same height as the links. At the rotation of the drum these projections enter the said openings and clean them during the passage of the chain grate around the drum. The other drum 5 is adjustable from the outside of the oven, so that the grate may be stretched, if required, by means of a stretching device 13. Under the driving drum 4 there is arranged a scraper 7 acting upon the chain grate by means of which the outer surface of the grate may be cleaned.

At the end of the oven, above the grate one or suitably two feeders 8, 9 are situated, the rear one 8 of which, in the direction of movement of the grate, being destined for coarser and the fore one 9 for finer material. At the feeding of the material into the oven the finer material thus will drop upon the coarser and thereby will be prevented from dropping down through the grate. The thickness of the two layers fed upon the grate may be regulated by adjustment of the intermediate partition wall between the funnels in vertical direction. After the distilling process the remaining goods is removed through a funnel 10, which suitably may be arranged in such a manner, that the goods resting after the distillation can be removed without thereby causing any loss of gas. The gas resulting from the distillation is removed through the outlet conduit m , after having been passed forward through the oven due to the partitions k and k' not closely fitting the grate or heating channel as has been explained before, and is then treated to remove the valuable constituents therefrom.

60 The chain grate after having passed the driving drum 4 runs to the drum 5 through a channel 12 under the chamber 15.

Having now particularly described the nature of our invention and the manner of its operation, what we claim is:

1. An apparatus for the distillation of bituminous shales, brown coal and the like, consisting of an elongated oven, a perforated grate travelling through the oven and dividing the interior of the oven into longitudinal chambers, channels in the side walls of the oven connecting and communicating with the longitudinal chambers, thus forming a passage for the circulation of the gases of distillation, heating means in the said passage and

- means for bringing the said gases in circulation.
2. An apparatus for the distillation of bituminous shales, brown coal and the like, consisting of an elongated oven, a grate composed of separate perforated bottoms travelling through the oven and dividing the interior of same into longitudinal chambers, channels in the side walls of the oven connecting and communicating with the longitudinal chambers, thus forming a passage for the circulation of the gases of distillation, heating means in the said passage, and means for bringing the said gases in circulation.
3. An apparatus for the distillation of bituminous shales, brown coal and the like, consisting of an elongated oven and an endless grate provided with perforations, driving drums for moving the grate and provided with projections cooperating with the perforations and serving to clean them, longitudinal chambers above and below the material supporting part of the grate, channels in the side walls of the oven connecting and communicating with the chambers, thus forming a passage for the circulation of the gases of distillation, heating means in the said passage, and means for bringing the said gases in circulation.
4. An apparatus for the distillation of bituminous shales, brown coal and the like, consisting of an elongated oven, a perforated grate travelling through it and dividing the interior of the oven into longitudinal chambers, channels in the side walls of the oven connecting and communicating with the longitudinal chambers, cross partitions in the upper and lower part of the oven chambers forming compartments therein which communicate with one another, means for circulating the gases and means for heating the gases arranged in the passage for the circulation of the gases.
5. An apparatus for the distillation of bituminous shales, brown coal and the like, consisting of an elongated oven, a perforated grate travelling through it and dividing the interior of the oven into longitudinal chambers, channels in the side walls of the oven, connecting and communicating with the longitudinal chambers, thus forming a passage for the circulation of the gases of distillation, a heating duct arranged in the said passage, and transverse tubes provided in the heating duct intended to be passed by and to heat the circulating gases of distillation.
6. An apparatus for the distillation of bituminous shales, brown coal and the like, consisting of an elongated oven, a perforated grate travelling through it and dividing the interior of the oven into longitudinal chambers, channels in the side walls of the oven connecting and communicating with the longitudinal chambers, thus forming a passage

for the circulation of the gases of distillation, heating means in said passage, two feeders above the feed end of the grate, one behind the other, and a vertically adjustable partition wall between the feeders for controlling the thickness of the layer of material fed to the grate from one of these feeders.

In testimony whereof we affix our signatures.

JOHAN GUSTAF GRÖNDAL. 75
CARL LORENS CARLSON.
